UNITED STATES PATENT OFFICE.

SAMUEL MATTSON, OF NEW YORK, N. Y.

HOISTING-MACHINE.

SPECIFICATION forming part of Letters Patent No. 643,516, dated February 13, 1900.

Application filed June 30, 1898. Serial No. 684,876. (No model.)

To all whom it may concern:

Be it known that I, SAMUEL MATTSON, of New York, (Brooklyn,) in the county of Kings and State of New York, have invented certain new and useful Improvements in Hoisting-Machines; and I do hereby declare the following to be a full, clear, and exact description of the invention, such as will enable others skilled in the art to which it appertains to make and use the same.

This invention contemplates certain new and useful improvements in hoisting-machines.

The object is to provide simple and highly efficient friction-drums for the bull-wheel rope which may be operated by one of the hoisting-rope drums of a hoisting-engine, thus leaving free for any other purpose the usual winch-head controlled by the other one of two hoisting-rope drums.

The invention will be hereinafter fully set forth, and particularly pointed out in the claims.

In the accompanying drawings, Figure 1 is a view in perspective, showing hoisting machinery provided with my improvements. Fig. 2 is an enlarged end view of the friction-clutches. Fig. 3 is a sectional view on line 3-3, Fig. 2. Fig. 4 is a detail.

Referring to the drawings, A A' designate the hoisting-rope drums of a hoisting-engine. Upon the shaft a of the drum A' is an ordinary winch-head a' , while carried by the shaft a^2 of drum A is a gear-pinion 1, the hub 2 of which is elongated and keyed on said shaft, said pinion being some distance outside of the ordinary frame 3, in which said shafts a and a^2 have their bearings.

B designates a supplementary frame or casting which is bolted directly to frame 3 by bolts passed through openings 4 in a flange 4 thereof. From this frame B project two studs or non-rotary shafts 5 and 6, the outer ends of which, as also the end of shaft a^2 , fit in openings in a triangular frame 7, held on said shafts by nuts 8. This frame serves to hold the several shafts firm and keep the gear-wheels in place. Upon each of the non-rotary shafts 5 and 6 is loosely mounted a gear-wheel 9, both of which mesh with and are driven by the gear-pinion 1. The inner face of each

gear-wheel has a continuous groove 10, preferably V-shaped.

C C' designate the drums on which the rope d of the bull-wheel D is wound. These drums 55 are loose on their respective shafts 5 6 and are each formed with the usual circumferential concavity to accommodate the rope. At its outer end each drum has an enlarged flange 12, formed with a continuous circular rib 13 60 to conform to the groove 10, in which it is designed to fit when the drum is moved longitudinally on its shaft against its gear-wheel. This movement of the drums is effected by cams 14 15 on shafts 5 and 6 bearing each 65 against a cam-like boss 16, preferably integral with the casting. These cams act in opposition to each other, so that when moved in unison one will force the adjacent drum tight up against its coacting gear-wheel, while the 70 other drum will be synchronously released by the turning of its cam and be free to revolve independently of its gear-wheel. Each cam has an arm 17, both of which are connected at their outer ends by a link 18 and 75 are under the control of a lever 19. By moving the latter both cams will be moved together, binding one drum and releasing the other. The bull-wheel rope will be thus wound on the former as it is unwound from 80 the latter. The drum in unwinding or paying out the rope will rotate in opposite direction to the gear-wheel with which it coacts when the rope is being wound thereon. By not tightening either drum both may rotate 85 independently of their gear-wheels. By thus controlling the winding and unwinding of the bull-wheel rope by two drums rotatable by a single one of the hoisting-rope drums the winch-head on the shaft of the other hoisting-rope drum is free to be used for any desired purpose.

D is the bull-wheel, on which the rope d is wound to effect the swinging of the boom d' and mast d^2 . The latter is suitably mounted 95 at its lower end in any preferred way.

The advantages of my invention are apparent to those skilled in the art to which it appertains.

I claim as my invention—

1. In a hoisting-engine, a drum, a gear-pinion rotatable therewith, two drums, gear-

wheels for the latter meshing with said pinion, and means for binding said last-mentioned drums to and releasing them from said gear-wheels.

5 2. In a hoisting-engine, a drum and shaft therefor, a gear-pinion on said shaft, a non-rotary shaft, a gear-wheel on the non-rotary shaft in mesh with said pinion, a drum on said non-rotary shaft, and means for binding 10 said drum to said gear-wheel, substantially as set forth.

3. In a hoisting-engine, a drum and shaft therefor, a gear-pinion on said shaft, two non-rotary shafts paralleling the first-mentioned 15 shaft, gear-wheels loosely mounted thereon meshing with said pinion, drums also loosely mounted on said non-rotary shafts, and means for binding said drums to, and releasing them from, said gear-wheels, substantially as set 20 forth.

4. The combination with a hoisting-engine, of two non-rotary shafts, gear-wheels loose on such non-rotary shafts, means for rotating said gear-wheels, drums also loose on said 25 shafts, and means for binding said drums to, and releasing them from, said gear-wheels, substantially as set forth.

5. The combination with a hoisting-engine,

a drum and shaft therefor, and a gear-pinion fast on said shaft, of two non-rotary shafts, 30 gear-wheels loose thereon, meshing with said pinion, drums also loose on said shafts, cams for binding said drums against said gear-wheels, and connections between said cams; whereby as one drum is bound to its gear-wheel the other drum will be released, substantially as set forth.

6. The combination with a hoisting-engine, a drum and shaft therefor, and a gear-pinion on said shaft, of a supplemental frame having 40 non-rotary shafts projecting therefrom paralleling the first-mentioned shaft, gear-wheels loose on said non-rotary shafts, meshing with said gear-pinion, drums also loose on said non-rotary shafts capable of frictional 45 contact with said gear-wheels, cams on said non-rotary shafts for binding said drums against said gear-wheels, and connections between said cams, substantially as set forth.

In testimony whereof I have signed this 50 specification in the presence of two subscribing witnesses.

SAMUEL MATTSON.
